ABSTRACT OF THE DISCLOSURE

A hermetic compressor in which a motor-compressor unit is resiliently suspended within a hermetic housing and a discharge tube extends within the housing from the compressor outlet to a connector tube which extends through the wall of the housing to the exterior of the compressor. The connector tube is in part supported on the wall of the housing by a rigid connection. The connector tube is also supported at a point spaced from the rigid connection and adjacent the discharge tube-connector tube interconnection by a bracket secured to the wall of the housing, and by a spring clip having legs inserted through the bracket and a center portion encircling the connector tube. The clip is self-retaining when mounted in assembled relation with the bracket and tube and also provides a resilient support for the tubes allowing limited flexure at their interconnection to relieve stresses.

This invention relates to hermetic compressors and more particularly to a mounting arrangement and construction for the discharge and connector tubes of the compressor.

An object of the present invention is to provide a hermetic compressor having improved means for supporting the discharge and connector tubes within the compressor housing.

Another object is to provide a compressor of the above character wherein said support means comprises a very simple and inexpensive spring clip bracket arrangement which eliminates the usual silver solder connection of the discharge connector tube to the bracket, thereby reducing manufacturing and assembling costs, and which also distributes and relieves the stresses of the flexing motion imparted to the discharge tube when the compressor vibrates in the housing, thereby reducing the possibility of failure of the connector tube support.

Other objects as well as features and advantages of the present invention will become apparent from the following detailed description taken in conjunction with the accompanying drawings wherein:

FIG. 1 is a side elevational view of a hermetic compressor incorporating the present invention, portions of the housing of the compressor being broken away to illustrate the motor-compressor unit mounted therein.

FIG. 2 is a horizontal sectional view taken on the line 2—2 of FIG. 1.

FIG. 3 is a fragmentary vertical section taken on the line 3—3 of FIG. 2, but on an enlarged scale.

FIG. 4 is a fragmentary sectional view taken on the line 4—4 of FIG. 3.

FIG. 5 is a fragmentary side elevational view of the discharge and connector tube joint illustrating the clip and bracket arrangement of the present invention.

FIG. 6 is a perspective view of the spring clip of the present invention shown by itself, on a still larger scale.

Referring in more detail to the accompanying drawings, FIG. 1 illustrates a compressor 10 which, as in conventional hermetic compressor construction, comprises a housing 12 made up of lower half shell casing 14 and an

2

upper half shell casing 16 respectively having circumferentially extending radial flanges 18 and 20 which are welded together to hermetically seal the housing. A conventional motor-compressor unit generally designated 22 is resiliently mounted within and in spaced relation from housing 12 and comprises an electric motor 24 which drives a twin cylinder piston compressor 26. Unit 22 is resiliently supported by three spaced coil springs 28, only one of which is shown in FIG. 1, each mounted at its lower end on a bracket 30 secured to casing 14 and at its upper end to the crankcase-frame casting 32 of unit 22.

As is customary, compressor 26 has a discharge muffler 34 the outlet of which is connected to the inlet end 36 (FIG. 2) of a discharge tube 38, usually made of welded steel tubing, adapted to conduct compressed refrigerant gas from the muffler to an external connection via a discharge connector tube 40 (FIGS. 2—5). As best seen in FIGS. 1 and 2, tube 38 extends vertically upwardly from its inlet end 36 toward the top wall 39 of casing 16 and is then bent to an angle of about 90° so as to extend horizontally in an oblong loop 38a (FIG. 2) around the headspace of casing 16 in spaced relation between casing 16 and the intake separator structure 42 mounted on the upper end of motor 24. Loop 38a terminates near the inlet riser 36, where tube 38 is again bent 90° to extend downwardly to form an outlet portion 44 the lower end 46 of which terminates approximately at the elevation of flanges 18 and 20 (FIG. 3).

Outlet end 44 of tube 38 has a telescopic interconnection with the upper, inlet end 48 of tube 40, which connection may consist of end 44 sliding within end 48 (as shown in FIG. 3), or vice versa, the two ends 44 and 48 being securely united and held in sealed relation at their telescopic interconnection by a silver soldered joint 50.

Connector tube 40 is generally L-shaped, inlet end 48 forming the longer riser of the L and the shorter riser 52 being disposed externally of housing 12 for suitable connection to the refrigeration equipment served by compressor unit 10. The bight 54 of tube 40 extends through a circular opening 56 in the wall of casing 14 and carries a sealing flange 58 which abuts against the outer face of casing 14 and is securely fixed thereto by a silver solder joint 60 so that opening 56 is hermetically sealed. If desired, riser 52 may be omitted and the external portion of tube 40 may extend horizontally or may have any other suitable configuration to satisfy external hook up requirements.

In accordance with a principal feature of the present invention, discharge tube 38 and tube 40, considered as a two-piece rigidly interconnected assembly, are provided with additional semi-resilient support means disposed between the rigid connection 60 and the rigid connection of inlet end 36 with muffler 34. This additional support means comprises a stamped sheet metal bracket 70 and a one piece spring wire clip 72 best seen in FIGS. 3—6 inclusive.

Bracket 70 has a pair of oppositely extending end portions 74 and 76 (FIGS. 4 and 5) formed to lie against the cylindrical inner surface 15 of casing 14 and is secured to this surface by spot welds 78 and 80 (FIG. 5). As best seen in FIG. 4, bracket 70 is corrugated to form a center portion 82 having a convex surface 84 contacting surface 15 at the center of the bracket and a concave surface 86 against which end 48 of tube 40 nests. Portion 82 is flanked by a pair of crowns 88 and 90 having concave inner surfaces 92 and 94 respectively which are spaced from surface 15. When the parts are arranged and constructed to the scale illustrated in the drawings, bracket 70 is preferably oriented with its lengthwise dimension parallel to flange 18 of casing 14 with its upper edge approximately one quarter of an inch below the top surface of flange 18. Crown 82 of bracket

70 is preferably disposed in vertical alignment with the center line of aperture 56, with the mid-point of the bracket being about three inches above the center of aperture 56. Bracket 70 thus supports tube 40 with riser 48 thereof parallel and spaced from surface 15, the upper end edge 96 of riser 48 being positioned about three-eighths of an inch above the upper surface of flange 18. It is to be understood that joint 50 may be disposed further above clip 72, for example by as much as about three inches in an arrangement scaled to the present disclosure without sacrificing the improved results of the present invention.

Referring to FIG. 6, spring clip 72 preferably comprises a unitary piece of spring steel piano wire having a diameter of about one-sixteenth of an inch and a length of about 3.75 inches. This wire stock is bent to form a U-shaped bight portion 100 in the center of the wire which is adapted to extend horizontally (in the operative assembled position of clip 72 as shown in FIG. 3) around tube 40 so as to embrace the side of the tube remote from bracket 70. Clip 72 has a pair of identical legs 102 and 104 respectively dependant one from each of the ends of bight 100. Each arm 102 and 104 has a straight vertical portion 106 slightly longer than the vertical width dimension of bracket 70, a portion 108 bent toward bight 100 so as to curve away from surface 15, and a reversely bent portion 110 at the lower end of the leg which forms a smooth rounded protuberance adapted to bear slidably against surface 15 in the stressed condition of spring clip 72 when assembled as described hereinafter.

In the manufacture of compressor 10, connector tube 40 is installed in casing 14 prior to installation of motor-compressor unit 22 therein, tube 40 being secured to casing 14 at joint 60 after bracket 70 has been spot welded to casing 14. Preferably tube 40 is temporarily supported by clip 72 and bracket 70 prior to and during the silver soldering operation at joint 60. All that is required to so assemble tube 40 is to insert the riser end 48 from the exterior of the shell through aperture 56 and then turn the tube upright so that riser 48 lies against the center portion 82 of bracket 70. Clip 72 is then inserted on bracket 70 by placing bight 100 against tube 48 and, with feet 110 disposed one above and in alignment with each of the spaces defined by the surfaces 92 and 94 of the bracket and surface 15 of the shell, as best seen in FIG. 4, then shoving the clip downwardly along surface 15 so that feet 110 pass through these spaces. During this downward insertion movement, the upper edge of bracket 70 engages bowed portion 108 of each leg and cams the same toward surface 15, resilient legs 102 and 104 yieldably flexing and resisting this flattening deflection until portions 108 have cleared the bracket, whereupon portions 108 spring back to their position shown in FIG. 3. When the clip is thus fully inserted, straight portions 106 of the legs are pressed firmly against surfaces 92 and 94 of bracket 70 by the stresses developed in the deflection of feet 110 of the legs toward bight 100, thereby securely retaining clip 72 in the position shown in FIGS. 3 and 5 with bight 100 resting on the upper edge of bracket 70 and encircling and closely embracing the side of tube 40 disposed remote from surface 15. Clip 72 thus clamps tube 40 snugly against bracket 70, but due to the resilient nature of clip 72 a very slight deflection (in the order of a few thousandths of an inch) of the upper end 48 of tube 40 (to the left in the plane of the drawing as viewed in FIG. 3) can occur, clip 72 yielding and bending slightly to permit such deflection while resisting the same.

The assembly of compressor 10 is completed by mounting motor compressor unit 22 on its spring suspension structure in casing 14, and then connecting the outlet end 44 of discharge tube 38 to the inlet end 48 tube 40 as described previously. Due to the disposition of the upper edge 96 of tube 40 above flange 18, the junction 50 of these tubes is readily accessible for the silver soldering

operation. After this connection is made, the upper casing 16 is assembled on casing 14 and flanges 18 and 20 welded together to provide a hermetically sealed joint.

From the foregoing description, it will now be apparent that the discharge-connector tube construction of the present invention, and in particular bracket 70 and spring clip 72, provides a simple, low cost assembly and mounting arrangement which eliminates the necessity of using the prior art arrangement of silver soldering the discharge connector tube 40 to a bracket on the casing. In addition, it has been found that spring clip 72 overcomes the problem of the prior art silver soldered joint (between tube 40 and a casing bracket) breaking as a result of the stress imposed on this joint when unit 22 was subjected to severe vibration within and relative to housing 12, as during shipment. With clip 72, some of this stress is taken up in the clip 72 and bracket 70 and the remainder is distributed along tube 40 and tube 38 because of the small but significant deflection permitted tube 40 in the vicinity of bracket 70 by clip 72. This deflection may only be in the order of a few thousandths of an inch, but this has been found to be sufficient to reduce the stress concentrations at this point to overcome the problem of failure of the tube intermediate support structure. However, sufficient support remains, and deflection of the interconnection of tubes 38, 40 is sufficiently limited by clip 72, so that no undue stress is imposed on either joint 50 or joint 60.

We claim:

- 30 1. In a compressor having a motor-compressor unit resiliently suspended within a hermetic housing, the improvement comprising a discharge tube having an inlet at one end thereof connected to an outlet of said compressor unit, said discharge tube extending within said housing spaced from said unit and said housing and having an outlet at the end thereof opposite said inlet end, a discharge connector tube mounted on and extending through a wall of said housing and having an inlet end connected to said outlet end of said discharge tube at a point within said housing spaced from said wall thereof and support means secured to said housing and including a wire retainer having a bight portion at least partially embracing one of said tubes and yieldably clamping said tubes to said housing wall at a point between the connection of said discharge tube to said unit and the mounting of said connector tube on said wall.
- 35 2. In a compressor having a motor-compressor unit resiliently suspended within a hermetic housing, the improvement comprising a discharge tube having an inlet at one end thereof connected to an outlet of said compressor unit, said discharge tube extending within said housing spaced from said unit and said housing and having an outlet at the end thereof opposite said inlet end, a discharge connector tube mounted on and extending through a wall of said housing and having an inlet end connected to said outlet end of said discharge tube at a point within said housing spaced from said wall thereof and support means yieldably clamping said tubes to said housing wall at a point between the connection of said discharge tube to said unit and the mounting of said connector tube on said wall, said support means comprising a bracket disposed between said wall and said tubes, said bracket being fixed to said wall and having a portion spaced inwardly of said housing away from said wall, and a retainer having a first portion inserted in the space between said bracket portion and said wall and a second portion extending about and embracing one of said tubes to yieldably secure said one tube against said bracket.
- 40 3. In a compressor having a motor-compressor unit resiliently suspended within a hermetic housing, the improvement comprising a discharge tube having an inlet at one end thereof connected to an outlet of said compressor unit, said discharge tube extending within said housing spaced from said unit and said housing and having an outlet at the end thereof opposite said inlet end, a
- 45
- 50
- 55
- 60
- 65
- 70
- 75

discharge connector tube mounted on and extending through a wall of said housing and having an inlet end connected to said outlet end of said discharge tube at a point within said housing spaced from said wall thereof and support means yieldably clamping said tubes to said housing wall at a point between the connection of said discharge tube to said unit and the mounting of said connector tube on said wall, said support means comprising a corrugated metal bracket having a center portion with a convex surface facing said wall and a concave surface opposite said convex surface, two crowns flanking said center portion, each of said crowns having a concave surface facing said wall, and two extremities fixed to said wall, one of said tubes nesting in said concave center portion surface of said bracket, and a resilient retainer having a center U-shaped bight portion embracing said one tube and two legs with one of said legs dependent from one end of said bight portion and the other leg from the other end of the bight portion, one leg being inserted in the space between one of said crowns and the adjacent surface of said wall and the other leg in the space between the other crown and said wall.

4. The compressor set forth in claim 3 wherein said retainer comprises a spring steel wire and wherein each of said legs has a straight portion extending at right angles to bight portion a distance about equal to the dimension of said bracket parallel to said connector tube, said leg then being curved inwardly of said housing away from said wall and then curved outwardly of said housing toward said wall and terminating in a rounded foot portion bearing slidably against said wall, said spring wire being stressed when so mounted.

5. The compressor set forth in claim 4 wherein said tubes run vertically at said interconnection therebetween and said spring retainer legs are inserted downwardly into said bracket spaces.

6. In a compressor having a motor-compressor unit resiliently suspended within a hermetic housing, the improvement comprising a discharge tube having an inlet at one end thereof connected to an outlet of said com-

pressor unit, said discharge tube extending within said housing spaced from said unit and said housing and having an outlet at the end thereof opposite said inlet end, a discharge connector tube mounted on and extending through a wall of said housing and having an inlet end connected to said outlet end of said discharge tube at a point within said housing spaced from said wall thereof and support means yieldably clamping said tubes to said housing wall at a point between the connection of said discharge tube to said unit and the mounting of said connector tube on said wall, said housing having upper and lower casings joined at a circumferential seam and said connector tube being mounted in said lower casing and extending therethrough at a point spaced below said support means, said support means comprising a retainer and a bracket supporting said retainer with said bracket being disposed on said lower casing near said seam, said interconnection of said tubes being above said bracket near said seam.

7. The compressor set forth in claim 6 wherein said retainer clamps said tube against said bracket and said retainer has limited resilient yielding movement relative to said bracket and housing to permit slight flexing of said tubes in the vicinity of said tubes interconnection relative to the through-connection of said connector tube with said casing.

8. The compressor as set forth in claim 7 wherein said connector tube is silver soldered to said lower casing at said through-connection therebetween.
